KNIFE MOUNTED ON A HAND OPERATED CARRIAGE FOR DETACHING A STRIP OF MATERIAL FROM A ROLLER

Carl Neubronner, Kornberg (Taunus), Germany

Application December 1, 1951, Serial No. 259,323

17 Claims. (Cl. 164—42)

The present invention relates to a device for detaching a strip of material, more particularly a gummed tape, from a reel and includes the cutting off of said strip.

It is the object of the present invention to provide a device of this kind which comprises simple means for feeding the strip to the position where it is to be cut off and for effecting the cutting operation.

It is another object of the invention to provide a device which is inexpensive to build and simple to operate.

Other advantages and objects of the invention will become apparent from the following specification.

In the known devices of the type above indicated, a strip of material is passed by hand with the aid of an idler member over a guide-track at the end of which the strip is cut off, likewise by hand, by means of a knife arranged at this spot. The disadvantage of the known devices of this type consists in the fact that for pulling the strip down on the track and for cutting it off, separate parts have to be provided and separate operational steps have to be made. In some devices, the detaching of the material, for instance gummed tape, is done by friction rollers, knurled wheels, or parts designated as idlers, whereas the severing of the strip is effected by means of a knife arranged at the end of the feed path.

The disadvantages of the known devices are overcome according to the invention by providing a single means for feeding the strip along a guide-track and cutting the same at the end of the track in a single operational step.

The invention comprises many other features which will be more fully explained below.

Examples of the device according to the invention are illustrated in the accompanying drawing, in which:

Fig. 1 is a longitudinal section through the device;

Fig. 2 a front view of the same;

Fig. 3 is a section taken along line A—B in Fig. 2;

Fig. 4 an enlarged view of the part marked C—D in Fig. 1; and

Fig. 5 is a different embodiment of the knife.

The device comprises, as illustrated in the drawing, a casing 1, in which a reel 2, for instance a reel of gummed tape, is mounted for rotation on a pin 3. Casing 1 is closed at the front and houses an elongated guide track 4. The guide track comprises a bottom 5, for instance of metal, and a plate 6 lying beneath the bottom and bent up on both sides around the same. These marginal parts form lateral guide rails 6a for a tape 7 wound off reel 2 and passed over the bottom 5. Plate 6 may be made of sheet metal or other suitable material. It is, however, desirable to make the plate of a transparent material.

The tape, extending over guide track 4 between the rails 6a, is visible so that the operator is able to measure the length of the strip to be cut off as desired. The advantage of the strip being visible is even more pronounced when a transparent plastic is used and the determination of the length of strip can be enhanced by providing a scale for measuring the length on the guide rails.

On both sides of the track, round bars 8 are arranged in which a sliding carriage 9 is guided for longitudinal movement. A curved knife 11 is mounted on carriage 9 rotatable on a pin 10, said knife having a pointed triangular cutting face. The cutting face could also be of different shape. The knife is mounted on a support 11a provided with a knurled cover 12 made of rubber, plastic or the like. The knurling may also be directly cut into the surface of the knife support. It is advantageous to make the knife exchangeable on the support. The carriage 9 and the knife 11 are held in elevated position by

means of two tension springs 13 made of spring wire, one of the springs being arranged on each side in the interior of the casing. The springs are attached with one end at 14 at the carriage 9, with the other end at 15 at the front of the inner casing wall. Instead of the tensioning spring arrangement, there may be spring arrangements of different kinds.

As shown more particularly in Fig. 4, guide track 4 terminates at the lower end and close to a transverse slot 16. In the slot there is an abutment ledge 17 which on one side is provided with a flap 17a extending over guide bars 8 (see also Fig. 3), and which on the other hand is pushed, under the action of springs 18, against the lower edge of guide track 4. At the lower end of the device, a flat guide member 19 is arranged for taking up the tape emerging from the side rails 6a, said member having the purpose of pressing the gummed strip against a brush 21, projecting from a water container 20.

The device according to the invention operates as follows:

When it is desired to cut off a strip, knife 11, which is preferably held by an articulated spring (not shown in the drawing) at a short distance above the bottom 5, is pressed by a slight pressure of the operator's finger onto this slide so that the knife will rest on the tape 7. Then, while still slightly pressing with his finger, the operator moves carriage 9 downward, along rails 8 until the end of the track is reached, where knife 11 pushes ledge 17 down against the action of spring 18, severs the part of the strip emerging from rails 6a and slides into the slot opening up between the end of the track and ledge 17. When, after severing the strip, pressure on bottom 15 is released by the operator lifting his hand, the knife will glide out of the slot and the latter will again be closed by ledge 17 while carriage 9 automatically returns to its starting position under the action of springs 13. Instead of a spring-actuated ledge 17 there may be provided a larger slot which gradually widens toward the top; or there may be other arrangements for the same or other purposes. For instance, an adjustable abutment member 23 may be provided which limits the sliding path of the knife upwardly and which may be adjusted for various lengths of strips.

As may be seen from the above described illustration, it is possible to effect the feeding of the strip and its cutting off by the same means in a single operation. It is thus possible to have a device of simpler design and simpler operation as compared to known devices in the field which require a separate means, which has to be operated individually for every function.

There may be many modifications of the device, illustrated by way of example. The knife support 12a, for instance, may be made as shown in Fig. 5. In this embodiment the support is pulled further down when rotated on pin 10 and may have an extended rear portion 22 covered by rubber or the like. In this embodiment the strip may be fed forward either by means of the attached knife point 11, or by means of extension 22, as desired.

While I have described and illustrated two preferred embodiments of the invention, it should be understood that these have been given by way of illustration and not of limitation, and that many other modifications and variations of the device may be made without departing from the spirit of my invention.

What I claim is:

1. A device for detaching a strip of gummed tape from a reel, which comprises a guide track for said strip, a hand-operated carriage arranged for sliding movement down said track, a knife mounted for rotation on said carriage, said knife being adapted for feeding said strip from said reel over said track, said track having an end face adjacent to a transversal slot, said end face and slot being adapted to cooperate with said knife in severing the strip.

2. A device according to claim 1, wherein means are provided for normally obstructing said slot at the end of said track, but capable of receding and of freeing an opening for receiving the knife to permit the cutting action.

3. A device according to claim 2, wherein the obstruct-

3

ing means consists of a ledge abutting against the end face of said guide track and of a spring acting on said ledge.

4. A device according to claim 1, wherein bars are provided for the guiding of said carriage in longitudinal direction along said track.

5. A device according to claim 1, wherein said knife is bent downwardly and has a point capable, while pressed down by the operator's finger, of feeding the strip of tape over the track and of severing the strip at the slot of the end of said track.

6. A device for detaching a strip of gummed tape from a reel, which comprises a guide track for said strip, a hand-operated carriage arranged for sliding movement down said track, a curved knife with a bent-down point, a support for said knife mounted for rotation on said carriage, said knife being exchangeably attached to said support and adapted for feeding said strip from said reel over said track, said track having an end face adjacent to a transversal slot, said end face and slot being adapted to a transversal slot, said end face and slot being adapted to cooperate with the point of said knife in severing the strip.

7. A device according to claim 6, wherein said knife support has a knurled surface.

8. A device according to claim 6, wherein said knife support is provided with a knurled cover.

9. A device according to claim 6, wherein said knife support is provided with a knurled cover of rubber.

10. A device according to claim 6, wherein said knife support is provided with a knurled cover of plastic.

11. A device according to claim 6, wherein said knife support is provided with an extended rear portion capable of resting on said guide track, and a rubber cover for said extended portion.

12. A device for detaching a strip of gummed tape from a reel, which comprises a guide track for said strip, a hand-operated carriage adapted to slide upon said track, a knife mounted for rotation on said carriage, said knife being adapted for feeding said strip from said reel over said track, said track having an end face adjacent to a transversal slot, said end face and slot being adapted to cooperate with said knife in severing the strip, and a spring means for holding said carriage and the knife mounted

thereon at the top end of said track before operation is started.

13. A device according to claim 12, wherein said device comprises a casing and said spring means comprise two tension springs, one spring being arranged on each side inside said casing and attached with their one end to the walls of the casing and with their other ends to the carriage.

14. A device for detaching a strip of gummed tape from a reel, which comprises a guide track for said strip, a hand-operated carriage adapted to slide upon said track, a curved knife with a bent-down point, a support for said knife mounted for rotation on said carriage, said knife being exchangeably attached to said support and capable of feeding said strip from said reel over said track, said track having an end face adjacent to a transversal slot, said end face and slot being adapted to cooperate with the point of said knife in severing the strip, and spring means for holding said carriage and the knife mounted thereon at the top end of said track before operation is started.

15. A device according to claim 1, said track comprising a bottom and a plate underneath the same, said plate having formed thereon lateral portions bent upwardly and forming side rails for guiding the strip of tape on the track.

16. A device according to claim 15, wherein said plate consists of a transparent material.

17. A device according to claim 1, comprising a member arranged on the track for limiting the upward movement of the knife thereon.
